UNITED STATES PATENT OFFICE

2,066,673

DEVICE FOR CONVEYING HIGH-VOLATILE FUEL

Torbjörn Viktor Dillström, Stockholm, Sweden,
assignor to Hesselman Motor Corporation, Ltd.,
London, England, a corporation of Great
Britain

Application October 22, 1932, Serial No. 639,062
In Germany October 29, 1931

6 Claims. (Cl. 123—139)

This invention relates to a conveying device for relatively high-volatile fuel of the kind having parts which are lubricated with lubricating oil. The attempts hitherto made to utilize, for such fuels, the pumps employed, especially in internal-combustion engines, for the injection of relatively non-volatile fuels, have mostly failed because no effective means was available for preventing the fuel from passing from the pump 5 into the parts lubricated with lubricating means, so as to prevent for instance dilution of the lubricating oil and consequent damage to said parts.

It is the principal object of the present invention to obviate the foregoing drawback in a simple manner. To this end, according to the invention, at those places where the fuel (leakage in particular) could find its way out of the pump to the parts lubricated with lubricating means, the escaping fuel is vaporized by suitable means, such as a current of air.

In order more clearly to understand the invention, reference is made to the accompanying drawings which illustrate, partly in section, embodiments of conveying devices in accordance therewith.

Fig. 1 is a side elevation of an internal combustion engine with a conveying device embodying the invention and Fig. 2 is a central longitudinal section on an enlarged scale of a one-cylinder pump device, similar to the multicylinder pump shown in Fig. 1.

In said drawings A denotes an internal combustion engine with induction pipe B and throttle valve C. From the crank shaft D of the engine a pump 1 and a fan E are driven by suitable means as the gear F and the belt G.

Turning now to Fig. 2 reference numeral 1 denotes the casing of a fuel pump composed of the piston 2, pump barrel 3, suction pipe 4, inlet valve 5, delivery valve 6 and the delivery pipe 7 leading to an injection nozzle.

The piston is actuated from the camshaft 8 by way of the roller tappet 9 during the delivery stroke, and by the recoil spring 17 during the suction stroke.

The pump and actuating gear are mounted in a casing 10 enclosing a chamber 11 in which the tappet drive and the piston meet. On the one side, said chamber 11 is provided with an inlet 12, and on the other with an outlet 13, for an air current that is passed through the chamber 11.

In the embodiment shown, the air current forms the means for vaporizing the fuel leaking 55 from the fuel pump, and this air current can be

generated in various ways. Thus a pipe 14 attached to the outlet 13, may lead to the induction pipe B of the internal combustion engine shown in Fig. 1, into the combustion chamber of which gasoline is injected by the pump 1. In such case, 5 a powerful current of air is drawn through the chamber 11 during the suction stroke. The ventilation may also be provided by a fan E which, when the pump is employed on a vehicle, may be the fan of the water-cooling system, as shown. 10

In order to increase the protection of the lubricated parts of the pump gear, a protective cap 15 is arranged around the tappet push rod in the chamber 11, which cap may also be provided with special means for wiping fuel off the push rod. 15 In this embodiment, the cap 15 is mounted in a fixed position in the chamber 11, for example by bolting it on to the throat 18 of the casing 10, so that the cap can serve, at the same time, as a support for the recoil spring 16 of the tappet. 20

It will be apparent that many changes and modifications may be made within the scope of the present invention. Thus pipe 14 may not lead to the induction pipe but to another point if so wanted.

What I claim is:

1. In combination, an internal combustion engine, means for supplying high-volatile fuel to the engine comprising fuel injecting means and a pump for forcing fuel to said injecting means, 30 said pump comprising a casing providing a barrel and a chamber below said barrel, a pump plunger in said barrel, a spring for actuating said plunger on its suction stroke, lubricated tappet means mounted in said casing below said chamber and reciprocable to actuate said plunger on its discharge stroke, and means for preventing flow to the lubricated portion of said tappet means of fuel leaking past said plunger comprising wiping means engaging said tappet and means for causing flow of air through said chamber between said wiping means and said plunger whereby to vaporize fuel leaking past said plunger.

2. In an internal combustion engine adapted to be operated with high-volatile fuel, fuel injecting means, a pump having a movable pumping member for forcing fuel to said fuel injecting means, lubricated pump actuating means including a part contacting said pumping member and an engine driven fan arranged to direct a current of air past the place of contact of said pumping member and said part whereby to vaporize fuel leaking from the pump before it can reach said lubricated pump actuating means.

3. In an internal combustion engine having an

- intake manifold, means for supplying high-volatile fuel to the engine comprising a pump having a plunger, a fuel chamber at one end of the plunger and lubricated means at the other end 5 of said plunger for actuating the plunger, a fan driven by said engine, means for directing a current of air produced by said fan past said other end of said plunger to vaporize fuel leaking past the plunger, and a conduit for conducting the air 10 and vaporized fuel to said manifold.
4. In combination with an internal combustion engine of the injection type to which high-volatile liquid fuel is injected, means for supplying high-volatile liquid fuel to the engine comprising 15 a plurality of fuel injectors, one for each cylinder of the engine, and a fuel pump unit adapted to be mounted on and driven by said engine, said pump unit having a portion including a plurality of pump plungers for forcing fuel separately to 20 separate injectors, a base portion housing lubricated shaft and tappet mechanism for operating said plungers, and an intermediate portion providing a space between the first mentioned portion and said base portion in which said plungers 25 and tappets contact, said intermediate portion having an inlet opening and an outlet opening, and means for causing a current of air to flow from the inlet opening through said space to the outlet opening over said tappets and plungers to 30 vaporize and conduct in vapor form from said space fuel leaking past said plungers.
5. In combination with an internal combustion

engine of the injection type, means for injecting high-volatile liquid fuel thereto, including an injector, a pump having a plunger, engine actuated mechanism for moving said plunger on its discharge stroke to force fuel to said injector, 5 said mechanism including lubricated bearing parts disposed immediately below said plunger in a position to be contacted by liquid fuel leaking past said plunger and means for causing flow of air through the space between said plunger 10 and said lubricated bearing parts to remove from the plunger in vapor form fuel leaking past said plunger before such leaking fuel can reach any of said lubricated bearing parts.

6. In combination with an internal combustion 15 engine of the injection type, means for injecting high-volatile liquid fuel thereto, including an injector, a pump having a plunger, engine actuated mechanism for moving said plunger on its discharge stroke to force fuel to said injector, said 20 mechanism including lubricated bearing parts disposed immediately below said plunger in a position to be contacted by liquid fuel leaking past said plunger and conduit means connecting the space between said plunger and said lubricated 25 bearing parts with the air intake of the engine for causing flow of air through said space to vaporize and remove from the pump in vapor form fuel leaking past said plunger before such leaking fuel can reach any of said lubricated 30 bearing parts.

TORBJÖRN VIKTOR DILLSTRÖM.
